UNITED STATES PATENT OFFICE.

GEORGE W. LE COMPTE, OF BALTIMORE, MARYLAND.

DESIGN FOR A HAME-STRAP LOOP.

SPECIFICATION forming part of Design No. 35,259, dated November 5, 1901.

Application filed September 16, 1901. Serial No. 75,628. Term of patent 3½ years.

To all whom it may concern:

Be it known that I, GEORGE W. LE COMPTE, a citizen of the United States, residing at Baltimore, in the State of Maryland, have invented and produced a new and original Design for Hame-Strap Loops, of which the following is a specification.

Referring to the accompanying drawings, forming part hereof, Figure 1 is a perspective view of my hame-strap loop, showing my new design. Fig. 2 is a side elevation thereof.

Like letters of reference designate like parts in both views.

The loop A is formed with the outwardly curved sides a and a' , curvilinear in cross-section, and said loop is shaped to conform to the general contour of a hame-section. One end of this loop is drawn out and shaped in the form of a short cross-bar a^2 , suitable for engagement with the usual rack or stops on the side of a hame-section. An oppositely-situated and wider cross-bar a^3 , cylindrical in form, connects the sides of the loop and serves to hold the hame-strap, which is intended to be doubled around said cross-bar. The sides a and a' extend beyond this cross-bar a^3 in substantially straight parallel lines and are

bent upwardly out of the plane of the loop itself, as seen at b b' , and the ends of said extensions are bent inwardly to form short 30 alining elbows c c' , between which there is a gap. In other words, the ends do not meet. The essential, leading, or material feature of my design consists of the hame-strap loop, as shown and above described, with these elbowed extensions disposed at an angle to the plane of the loop itself and the elbows parallel with the cross-bar a^3 and separated by a gap, forming a rectilinear shape. The parts 35 b b' and c c' are smoothly rounded off to form 40 a smooth contact.

Having described my invention, what I claim as new, and desire to secure by Letters Patent, is—

The design for a hame-strap loop, as herein 45 shown and described.

In testimony whereof I have signed my name to this specification in the presence of two subscribing witnesses.

GEO. W. LE COMPTE.
